(57) CLAIM

The ornamental design for portions of a figurine, as shown and described.

DESCRIPTION

FIG. 1 is a perspective view of portions of a figurine showing my new design;

FIG. 2 is a front view thereof;

FIG. 3 is a right side view thereof;

FIG. 4 is a left side view thereof;

FIG. 5 is rear view thereof;

FIG. 6 is a top view thereof;

FIG. 7 is a perspective view showing a second embodiment of my design;

FIG. 8 is a perspective view showing a third embodiment of my design;

FIG. 9 is a perspective view showing a fourth embodiment of my design; and,

FIG. 10 is a perspective view showing a fifth embodiment of my design.

The broken lines shown in the FIGURES are environmental only and form no part of the claimed design.
